UNITED STATES PATENT OFFICE.

WESLEY A. THOMAS AND JOHN P. PELEGRIN, OF MEMPHIS, TENNESSEE.

BARREL.

No. 926,623.

Specification of Letters Patent.

Patented June 29, 1909.

Application filed July 2, 1908. Serial No. 441,609.

To all whom it may concern:

Be it known that we, WESLEY A. THOMAS and JOHN P. PELEGRIN, citizens of the United States, residing at Memphis, in the county of Shelby and State of Tennessee, have invented certain new and useful Improvements in Barrels; and we do hereby declare the following to be a full, clear, and exact description of the invention, such as will enable others skilled in the art to which it appertains to make and use the same.

Our invention relates to improvements in barrels, and the object of our invention is to provide a barrel useful for various purposes, such as a sauer kraut barrel, and one in which a removable cover or closure may be firmly attached to the barrel without the use of any metal inside the barrel, and provided with a movable plunger capable of being locked in various positions, so that pressure may be kept upon the contents of the barrel as desired.

With these objects in view, our invention consists of the construction and combinations of parts, as hereafter described and claimed.

In the accompanying drawing—Figure 1 is a vertical section of a barrel embodying our improvements. Fig. 2 is a top plan view of the same, partly in section. Fig. 3 is a detail view, on an enlarged scale, showing the method of attaching the cover to the barrel on one side. Fig. 4 is a similar view taken from the opposite side, and Fig. 5 is a top plan view of the slat plunger, the handle or operating lever therefor being shown in section.

a represents a barrel made in the usual way and provided with a bottom *b* and hoops *c* preferably of metal. Within this barrel a plunger is adapted to work which consists of slats *d* joined to cross pieces *e*, the whole being provided with a handle or operating lever *f* which passes vertically through a central aperture in the cover and is pivotally attached to one of the slats or wires *d*. This cover is made in two parts *g* and *h* hinged together. The part *g* is provided with wooden pins *i* which project outwardly and away from each other, as shown in Fig. 2, and are adapted to engage the chime of the barrel, as shown in Fig. 3. To secure the part *g* to the barrel it is provided with a right-angled bracket *j* and a screw *k* adapted to fit underneath one of the hoops. When

the screw is turned home the bracket and the pins *i* firmly hold the part *g* in position on the top of the barrel. On top of the part *h* and secured thereto are two parallel bars *m* and *n* which are perforated and engage the pintle *o* which is carried in brackets *p* on the part *g*. The bar *n* is cut away, as shown at *q*, and in this cut-away portion is mounted a pin *r* on which is pivotally mounted a spring arm *s* provided with an operating projection *t* and an eccentric *u*, and on the part *h* is a toothed rack *v* with which the arm *s* is adapted to engage. The handle *f* of the plunger projects up through the aperture in the cover opposite to the pin *r*, and it is obvious that by turning the arm *s* the eccentric *u* will be caused to lock the handle *f* in any desired position, or to release it, as desired. Pressure can, therefore, be put upon the handle *f* and then the plunger locked in any desired position. To hold the part *h* firmly down against the top of the barrel, the latter is provided with a spring clip *w* expanded out at the top, as shown at *x*, and adapted to fit over the ends of the bars *m* and *n*, as shown in Fig. 2.

The operation is as follows:—The part *g* being firmly fixed upon the barrel, the plunger is drawn up against the bottom of the part *h*, and then the part *h* and the plunger are folded back affording free access to the barrel. The interior of the barrel is then filled, or partly filled, with the sauer kraut or other material, and the plunger and the part *h* are turned down over the barrel and the part *h* is locked by means of the wire clip, the arm *s* during all this time being so turned that the handle *f* of the plunger will move freely. The desired pressure is then put upon the handle *f*, forcing the plunger down upon the material, and the arm *s* is turned locking the handle *f* in the desired position, thus keeping the solid material in the barrel under a definite pressure.

We claim:—

1. The combination of a barrel, a cover therefor composed of two parts hinged together, one of said parts being provided with devices for securing it to the top of said barrel, fastening devices carried by said barrel for securing the other part of said cover upon said barrel, said cover being provided with a central perforation, a plunger, an operating handle therefor passing through the perforation of said cover, an arm provided

with an eccentric for engaging said handle, and a rack with which said arm is adapted to engage, substantially as described.

2. The combination of a barrel, a cover therefor made in two parts hinged together, fastening devices for securing said cover to said barrel, said cover being provided with a central perforation, a plunger, an operating handle pivotally connected to said plunger and passing through the perforation in the barrel cover, an arm provided with an eccentric adapted to engage said handle, and a rack with which said arm engages, substantially as described.
- 5 3. The combination of a barrel, and a cover therefor made in two parts hinged together, one of said parts being provided with wooden pins extending outwardly and away from each other and with a bent bracket having a securing screw, and the other of said parts being provided with bars, and a fasten-

ing device carried by said barrel and adapted to engage said bars, substantially as described.

4. The combination of a barrel, a cover therefor made in two parts hinged together, one of said parts being provided with wooden pins projecting outwardly and away from each other and adapted to engage the chime of the barrel, and also with a right angled bracket having a set screw, and the other of said parts being provided with bars across its top, and a fastening device carried by said barrel for engaging the ends of said bars, substantially as described.

In testimony whereof, we affix our signatures, in presence of two witnesses.

WESLEY A. THOMAS.
JNO. P. PELEGRIIN.
